THE MORRIS PETERS CO., PHOTO-LITHO., WASHINGTON, D. C.

UNITED STATES PATENT OFFICE.

SAMUEL J. BALLARD, OF LOS ANGELES, CALIFORNIA, ASSIGNOR OF THREE-FOURTHS TO CALVIN W. BROWN, OF LOS ANGELES, CALIFORNIA.

GUARD FOR SPEECH RECEIVERS OR TRANSMITTERS.

SPECIFICATION forming part of Letters Patent No. 719,987, dated February 10, 1903.

Application filed July 2, 1901. Serial No. 66,921. (No model.)

To all whom it may concern:

Be it known that I, SAMUEL JUDSON BALLARD, a citizen of the United States, residing at Los Angeles, in the county of Los Angeles and State of California, have invented a new and useful Guard for Speech Receivers or Transmitters, of which the following is a specification.

This invention comprises a holder for holding a plurality of protecting-sheets in proximity to the mouthpiece or earpiece of the sound transmitter or receiver. It includes the appliance and parts herein described and claimed. Preferably the sheets are perforated and pivoted on a pin and retained thereon by a suitable retainer, and means are provided for pressing the leaves toward the retainer, said leaves being adapted to be moved one at a time in front of the mouth-piece or earpiece.

This invention is designed to provide a clean removable covering for telephone mouth and ear pieces which can be changed at will by pulling off one slip or sheet and turning into place over the aperture of the instrument a clean slip or sheet which has not theretofore been breathed upon or touched by a user of the instrument.

It is a well-known contention with physicians that contagion can be spread through the promiscuous use of the telephone by diseased people, besides which it is not pleasant to use a public telephone which may have just before been used and breathed, smoked, or even coughed into or which may have been held against the perspiring ear by some person of doubtful cleanliness. For reasons conducive to good health alone many would not consent to hold hands with an unknown person for the length of time of an average telephone conversation, but yet find it necessary to press the ear for minutes to an instrument that has been held in close contact with another's ear with its possible accumulation, infection, and contagion.

An object of my invention is to obviate the likelihood of such contagion and to promote a feeling of safety as well as cleanliness when properly used.

Another object is to keep the instruments free from dust and moisture.

Another object is to provide a useful device by means of which advertisements may be made acceptable to be placed and kept in constant view where they would not otherwise be admitted.

Another object is to provide a convenient tablet on the mouthpiece on which may be written memoranda, such as telephone-numbers or names of parties desiring to be called up by some particular person. This memoranda can be removed by tearing off the marked sheet without disturbing the one in place over the aperture of the instrument, and the marked sheet may be carried away for reference, thus further disseminating the advertisement.

Another object is to provide a sanitary guard for telephones, earpieces, and mouth-pieces which may be easily replenished by any ordinary printer.

Another object is to combine in such sanitary guard a business-card of the telephone owner giving his telephone-number, so that the user of the telephone will have in view the number of the telephone to which the device is applied. Such information being on a convenient card or slip which can be easily detached and carried away for reference also adds to the value as an advertising medium.

A further object of supplying a memorandum-space to be used by the user of the telephone is to prevent the mutilation or marking of walls by the making of memoranda on the walls.

The accompanying drawings illustrate my invention.

Figure I a perspective view of the invention with the protecting leaves, slips, or sheets and in use as an attachment to a telephone-transmitter. Fig. II shows the device in use on a telephone-receiver. Fig. III is a perspective view of the device ready for attachment to a transmitter or receiver. Fig. IV is a view of a sheet-metal blank adapted to be used in the manufacture of the holder. Fig. V is a side view showing the holder ready to receive the protecting sheets or slips. The sheet-retainer is shown detached. A cross-section of the pin is also shown. Fig. VI is a front view of one of the protecting slips or sheets. Figs. VII and VIII are front

views, respectively, on a reduced scale, of a frame formed in one piece and a blank for forming such frame. Fig. IX is a transverse sectional view, on an enlarged scale, of the pin portion of Fig. VII.

1 indicates a plurality of protecting slips or sheets of paper or any other suitable material. Paper of any desired thickness may be used, as I have found by experiment that 10 two sheets of thick blotting-paper will not prevent the ready transmission and reception of sound through the telephone. 2 indicates in a general way a holder for said sheets adapted and arranged to hold said sheets or 15 slips in position for being respectively and successively moved into position in front of the instrument to which it is adjusted.

In practice the outside slip or sheet *a* or the one next thereto can be turned into position across the mouth of the instrument, as indicated in Figs. I and II.

3 indicates the transmitting or receiving appliance, to which the holder will be attached by a clamp 4. The holder comprises 25 a standard 5, connected with the clamp 4, and a leaf-supporter, as a guide 6, fastened to the standard to guide the edges of the leaves or slips.

7 indicates a post or pin extending along- 30 side the guide at a distance therefrom to pass through perforations 8 in the protecting slips or sheets. The pin 7 is fastened to the support 5 and is furnished with two opposite notches 9.

35 10 indicates a sheet or slip retainer to retain the slips or sheets in place on the pin 7. This retainer is preferably made of a thin strip of metal perforated with a hole 11 to pass over the pin 7 freely and furnished with 40 a slot 12 to embrace the neck formed between the notches 9 in the pin. Resilient means are provided for pressing the leaves 1 toward the retainer 10.

13 indicates a spring for this purpose. The 45 free end of the spring is preferably expanded, as shown, and acts as a back or support to bear the pressure upon the leaves when they are being written upon.

The clamp 4, standard 5, and guide 6 are 50 preferably all formed of a single piece of bent sheet metal. 14 in a general way indicates a blank from which said parts will be pressed into shape.

15 indicates a clamp bolt and nut for clamp- 55 ing the frame on the earpiece or mouthpiece.

In practical use the appliance will be fastened to the telephone or other mouthpiece or earpiece, and a bunch of slips perforated with a hole 8 will be placed on the guides 6 and 60 over the pin 7 and will be secured by a suitable retainer, such as that shown at 10, the spring 13 being compressed to admit of the insertion of the sheets between the standard 5 and the retainer 10. The pressure of the 65 spring 13 constantly holds the sheets forward in position against the retainer, and the user whenever he desires may turn a sheet to bring

it past the ends of the guide 6, which for this purpose terminate rearward of the notch-formed seat 9 in the pin. When the sheet is 70 turned into position across the opening of the receiver or transmitter, the appliance is ready for use. It is to be understood that the slips *a* may be wholly or partially given over to advertising or advertisements may be omitted, 75 at the pleasure of the user, without departing from the broad spirit of my invention. When the user desires to provide a new surface, he will tear off the old slip and turn a new slip 80 into place.

The retainer 10 is preferably expanded and extends in two directions from the hole which receives the pin 7, and one arm of it serves to hold the sheet or slip against the mouthpiece or earpiece, as the case may be, and the other 85 arm holds the sheets or slips against the pressure of the spring 13.

16 indicates a cross-bar formed of the sheet from which the members 4 4 5 and 6 6 are bent. 90

17 18 indicate holes in the standard 5 for fastening the pin 7 and spring 13, respectively, to said standard.

Figs. I to IV show the pin riveted in the hole 17 and the spring 13 inserted in hole 18 95 and soldered fast.

In bending the frame comprising the cross-bar 16, clamp members 4, standard 5, and guide members 6 the clamp members 4 will first be bent forward at the dotted lines *x* and 100 then at the dotted lines *y*. The members 6 will be bent forward at the dotted lines *z*, thus leaving the bar 16 and the standard 5 at one edge of the bar in one common plane, the guide-arms 6 projecting forward lengthwise 105 from the bar at the edge thereof from which the standard projects and the clamp-arms 4 projecting edgewise from the bar opposite the guide-arms.

In the form shown in Figs. VII and VIII 110 the tongue 51, which is provided with notches 91 to form the retainer-seat, will be bent at the cuts *w* and will then be bent downward into tubular form to form the pin 71. (Shown in Fig. VII.) The tube thus formed may be 115 fastened at *w* by solder. In this form the standard corresponding to the standard 5 in Fig. IV is formed in two members 53, respectively, on the opposite sides of the member 71, which forms the pin. 120

The designating-number of the telephone to which the device is applied may be stamped on or otherwise applied to the face of the retainer, thus to inform the user of the telephone as to the number thereof. 125

What I claim, and desire to secure by Letters Patent of the United States, is—

1. A leaf-holder for speech receivers and transmitters comprising a base, a leaf-supporter projecting rigidly therefrom, and 130 means for engaging with one edge of it and retaining the leaf in or out of position.

2. A leaf-holder for speech receivers and transmitters comprising a base, a leaf-sup-

porter projecting rigidly therefrom, and detachable means for engaging with one edge of it and retaining the leaf in or out of position.

5. A leaf-holder for speech receivers and transmitters comprising a base, a leaf-supporter provided with a retainer at its outer end, and a guide for holding the leaf out of position, said guide being of a less length than the supporter, and means for forcing the leaves forward, whereby the outer leaf may be moved in its own plane between the end of the guide and the retainer into its operative position.

15. 4. A leaf-holder for speech receivers and transmitters comprising a base, a leaf-supporter projecting therefrom, provided with a retainer at its outer end, a guide below the supporter for holding the leaf out of position, the outer edges of said guide lying in vertical planes upon opposite sides of the center of the supporter and the end terminating to the rear of the retainer, and means for forcing the leaves forward, whereby the outer leaf may be swung in its own plane between the guide and the retainer into position for use.

30. 5. A leaf-holder for speech receivers and transmitters comprising a base, a leaf-supporter projecting therefrom, a bifurcated guide below the supporter, and extending upon opposite sides thereof, a retainer on the outer end of the supporter at a short distance beyond the end of the guide and extending above and below the same for supporting the leaf in or out of position, and means for forcing the leaves upon the guide forward.

40. 6. A leaf-holder for speech receivers and transmitters comprising a base, a leaf-supporter projecting therefrom, the outer end of which is slotted, a perforated retainer provided with a contracted slot for engaging with the slotted portion of the supporter, a guide below the leaf-supporter, the forward end of which terminates at a short distance from the retainer, and means for forcing the leaves upon the guide forward.

50. 7. A leaf-holder for speech receivers and transmitters, comprising a base, a leaf-supporter projecting therefrom provided at its outer end with a retainer, a guide below the supporter, the outer end of which terminates a short distance from the retainer, and a spring for forcing the leaves on the supporter forward.

55. 8. A leaf-holder for speech receivers and transmitters comprising a base provided with clamping-arms for holding it in position, a leaf-supporter projecting from the base, the outer end of which is provided with a retainer, a leaf-guide below the supporter, the outer end of which terminates at a distance to the rear of the retainer, and a spring secured to the base at one end for forcing the leaves on the guide forward.

60. 9. A leaf-holder for speech receivers and transmitters comprising a thin flat base pro-

vided with spring clamping-arms and a two-part flat leaf-guide, the arms and the guide lying in planes at right angles to each other, and to the base, means for holding the free ends of the arms in position, a leaf-supporter above the guide, the outer end of which is provided with a retainer at a short distance in front of the guide, and a spring for forcing the leaves on the guide forward.

10. The combination, with a speech receiving and transmitting appliance, of a leaf-holder secured thereto, said holder being provided with a pin, a retainer on the outer end of the pin, a leaf-guide between the pin and the appliance, the end of which is at a short distance from the retainer and substantially in a line with the end of the instrument, said holder being adapted to hold a series of leaves in such position that the forward leaf can be moved in its own plane into position in front of the appliance, and means for automatically moving the leaves toward the retainer, whereby the end one may be moved into position for use.

11. A protector for speech appliances consisting of a sheet of fibrous material, and means connected with said appliance for normally holding said sheet out of use, said sheet being so held that it may be moved into position for use without being removed from said retaining means.

12. A protector for speech appliances consisting of a series of sheets of material and means connected with said appliance for normally holding said sheets out of use, the forward sheet of said series being so held that it may be moved into position for use without being removed from said retaining means, and means for moving the sheets forward whereby they may be successively moved into position for use.

13. A leaf-holder comprising a guide for the edges of the leaves; a pin for insertion through said leaves; a leaf-retaining member on said pin beyond the end of the guide; and resilient means for pressing the leaves toward the retaining member.

14. A leaf-holder comprising a standard; a pin projecting from said standard; a guide extending parallel with the pin; a retainer on the pin beyond the end of the guide; and means for pressing the leaves toward the retainer.

15. The combination of the holder-frame furnished with a clamp and with a projecting pin; a retainer on said pin; and means for pressing leaves toward the retainer.

16. The frame for a leaf-holder, composed of bent sheet metal formed in a bar, a standard on one edge of the bar, two guide-arms projecting lengthwise from the bar, and two clamp-arms projecting edgewise from the bar.

17. A frame for a leaf-holder composed of bent sheet metal formed in a bar, a standard on one edge of the bar, two guide-arms projecting lengthwise from the bar, two clamp-arms projecting edgewise from the bar, and a

pin projecting forward from the bar and formed of a tongue bent into a tube.

18. A leaf-holder for speech appliances comprising a leaf-supporter, an extended retainer on the outer end thereof and a bearing for the leaves at the rear, and means for normally holding the leaves out of position.

In testimony whereof I have signed my

name to this specification, in the presence of two subscribing witnesses, at Los Angeles, 10 California, this 27th day of June, 1901.

S. J. BALLARD.
